UNITED STATES PATENT OFFICE

CELESTINO ROSATELLI, OF TURIN, ITALY, ASSIGNOR TO FIAT SOCIETÀ ANONIMA, OF TURIN, ITALY

AEROPLANE CONTROL SWITCH

Application filed December 11, 1930, Serial No. 501,714, and in Italy October 9, 1930.

This invention relates to a device enabling the instructor or first pilot of a double control school or tourist aeroplane to promptly disconnect the second control held by the candidate or passenger, by simply pulling on a flexible transmission of the usual type which operates the device. When it is desired to place the second control again in working condition, it is sufficient to release the flexible transmission whereupon a spring of the device comes into action and besides clutching again the second control returns special safety devices adapted to reinforce the coupling to their initial position.

The accompanying drawings show by way of example a construction of the device. However, it is to be well understood that the arrangement of its component parts and the form thereof can be varied without departing from the spirit of this invention.

Figure 1 is a longitudinal section of the switch means.

Figure 2 is a further longitudinal section at right angles to Fig. 1.

Figure 3 is a view of one of the safety latches.

A fixed cylindrical casing is secured to the control lever holder 1 of the aeroplane and a slidable tube 3 is guided therein; the tube 3 has an upper flared portion forming a conical seat in which the socket 5 is fitted by its conical end and receives the control lever of the aeroplane.

A spring 6 pushes the slidable tube 3 through the disc 14 against the control lever socket 5 so as to tighten it therein. The control lever socket can turn in any direction, being universally mounted on the two pivots 7 and 8 at right angles to each other and fast with the tube 2.

In order to further secure the socket 5 on the conical seat 4 of the slidable tube 3 so that it cannot overcome the resistance of the spring 6, two latches 9 are slidably mounted within the horizontal tube 10.

The latches 9 are provided with lateral cylindrical projections 11 engaged by the slots 2 of the strap 13 welded to the disc 14 to which the pressure of the spring 6 is applied. The slots 12 are inclined so that by

lifting and lowering the strap 13, the two latches 9 are pushed outwardly and inwardly. When these latter are pushed outwardly, they engage two opposed holes 15 bored both in the outer fixed casing 2 and in the inner slidable tube 3. The disc 14 urged by the spring 6 bears against a circular inner collar 16 on the tube 3 pushing this latter upwardly until the two latches 9 have entered the holes 15. The socket 5 is locked in its conical seat and the second pilot or the candidate can control the aeroplane.

In order to disconnect the second control, the first pilot or instructor pulls the wire 17 of the flexible (Bowden) transmission lowering the disc 14 which withdraws the latches 9 releasing the socket 5, this latter becoming loose and no longer affecting the aeroplane control. In order to clutch in the second control the flexible wire 17 is released; the spring 6 will then return all the parts to their initial position.

I claim:

1. Aeroplane control switch comprising in combination, a holder for a control lever, a tubular member fixed co-axially in said holder, a tube telescopically mounted in said tubular member and having a flared outer end, a socket adapted to receive a control lever and connected by a Cardan joint to said tubular member through slits in said tube, a conical annular projection on said socket adapted to fit with the flared end of said tube and means for displacing said tube at will so as to clear said socket from said tube.

2. Aeroplane control switch comprising in combination, a holder for a control lever, a tubular member fixed co-axial in said holder, a tube telescopically mounted in said tubular member and having a flared outer end, a socket adapted to receive a control lever and connected by a Cardan joint to said tubular member through slits in said tube, a conical annular projection on said socket adapted to fit with the flared end of said tube, means for displacing said tube at will so as to clear said socket from said tube and means for locking said tube with said tubular member when said annular projection is engaged by said conical flared portion.

3. Aeroplane control switch comprising in combination, a holder for a control lever, a tubular member fixed co-axially in said holder, a tube telescopically mounted in said tubular member and having at its outer end a conical seat, a socket adapted to receive a control lever, a Cardan joint connecting said socket with said tubular member, an annular conical projection on said socket adapted to fit with said conical seat, a spring for lifting said tube and for bringing said conical seat into engagement with said annular projection, a traction member for lowering said tube, latches carried by said tube and adapted to engage with holes on said tubular member, when said tube is fully lifted and means operated by said traction member for disengaging said latches from the holes of said tubular member when the traction member is pulled.

4. Aeroplane control switch comprising in combination, a holder for a control lever, a tubular member fixed co-axially in said holder, a tube telescopically mounted in said tubular member and having at its outer end a conical seat, a socket adapted to receive a control lever, a Cardan joint connecting said socket with said tubular member, an annular conical projection on said socket adapted to fit with said conical seat, a spring for lifting said tube and for bringing said conical seat into engagement with said annular projection, a tubular guide member fixed transversely in said tube, latches movable in said guide member and adapted to engage with holes on said tubular member, when said tube is fully lifted, a strap across said guide member and having inclined slits engaging projections on said latches for releasing these latter from the holes on said tubular member, when said strap is lowered with respect to said guide member and a flexible traction member secured to said strap.

In testimony that I claim the foregoing as my invention, I have signed my name.

CELESTINO ROSATELLI.
